PHILANDER S. FOSTER, OF RICHMOND, MAINE.

Letters Patent No. 64,655, dated May 14, 1867.

IMPROVED ROAD-SCRAPER.

The Schedule referred to in these Letters Patent and making part of the same.

TO ALL WHOM IT MAY CONCERN:

Be it known that I, PHILANDER S. FOSTER, of Richmond, in the county of Sagadahoc, and State of Maine, have invented a new and improved Scraper; and I do hereby declare that the following is a full, clear, and exact description thereof, which will enable others skilled in the art to make and use the same, reference being had to the accompanying drawings, forming part of this specification, in which—

Figure 1 is a top view of my improved scraper.

Figure 2 is a vertical longitudinal section of the same, taken through the line $z z$, fig. 1.

Similar letters of reference indicate like parts.

My invention has for its object to furnish an improved scraper by means of which the snow may be removed easily and quickly from ice, streets, walks, yards, &c.; and it consists in the scraper having tilting bottom-boards, and adjustably pivoted to the runners; in attaching projections or side scrapers to the forward ends of the side-boards, to clear away the snow in front of the runners; and in the combination of an inside scraper with the main scraper, to move the snow back in said main scraper, the whole being constructed and arranged as herein-after more fully described.

A is the scraper, the side-boards a^1 of which are adjustably pivoted to the runners B. a^3 is the iron or steel plate, by means of which the snow may be separated from the ice or ground, and which is securely attached to the forward parts of the side-boards a^1 . a^2 are the bottom-boards, which are pivoted at their ends to the frame of the scraper A. The boards a^2 are connected to each other by having their edges pivoted to the cross-bar a^4 , so that the said boards may all move together. The pivoting pin of one of the bottom-boards extends out, and has an arm or lever, C; attached to it, by means of which the bottom-boards a^2 may be conveniently tilted or canted to discharge the load. D are projections, ploughs, or scrapers attached to the forward ends of the sides of the scraper to push the snow away from before the runners B. The runners B are made with their middle parts, b^1 , projecting upward, as shown in fig. 2, which said projecting parts b^1 have several holes formed through them for the reception of the pins E, by means of which the scraper A is pivoted to the said runners, so that the said scraper may be adjusted according to the character of the work to be done. If desired the pins E may be arranged with a lever or brake, so that the scraper may be raised or lowered as convenience in loading, transporting, or unloading may require. The runners B may be placed either upon the outer or inner sides of the side-boards a^1 , as may be desired. When scraping, the forward end of the scraper A is held down in contact with the surface of the ice or ground by raising the rear end of said scraper where it is held by the brace F, the upper end of which enters one or the other of the notches formed in the rear part of the scraper A. The lower end of the brace or support F is pivoted to the framework that connects the runners, and upon which the rear part of the scraper rests when lowered. In case the snow does not slide up the inclined bottom of the scraper readily, I use the scraper G to force it up. The scraper G fits into the scraper A, and rests upon and is held in proper position by the feet or guide-blocks g^1 . To the forward side of the scraper G are pivoted two arms or pointed bars, g^2 . In using the scraper G, it is placed upon the forward part of the scraper A, with the ends or points of the bars g^2 sticking into the ice; then, as the scraper A is drawn forward, the scraper G pushes the snow before it up the inclined bottom of the scraper A, until the forward end of said scraper raises the forward ends of the arms g^2 from the ice. H is a shaft, revolving in bearings in the rear part of the scraper A, having a crank formed upon one end, and having hooks attached to it for the attachment of the chains or ropes I, the forward ends of which are attached to the scraper G. This arrangement is used for drawing the snow into the rear part of the scraper A, or for unloading the said scraper through the rear end, the rear-end board a^5 of said scraper being hinged or pivoted at its upper edge, to enable this to be conveniently done.

What I claim as new, and desire to secure by Letters Patent, is—

1. An improved scraper, A, having tilting or pivoted bottom-boards a^2 ; and being adjustably pivoted to the runners B, constructed and operating substantially as herein shown and described and for the purpose set forth.
2. The combination of the inside scraper G and pointed rods g^2 with the scraper A, substantially as herein shewn and described and for the purpose set forth.
3. The combination of the crank-shaft H and ropes or chains I with the scraper A and inside scraper G, substantially as herein shown and described and for the purpose set forth.

The above specification of my invention signed by me this 19th day of February, 1867.

PHILANDER S. FOSTER.
